DOLL

Ruth J. Heyman, Birmingham, Ala.

Application May 17, 1952, Serial No. 19,765

Term of patent 3½ years

(Cl. D34—4)

To all whom it may concern:

Be it known that I, Ruth J. Heyman, a citizen of the United States, residing at Birmingham, county of Jefferson, State of Alabama, have invented a new, original, and ornamental Design for a Doll, of which the following is a specification, reference being had to the accompanying drawing, forming a part thereof.

Fig. 1 is a front elevational view of a doll showing my new design;

Fig. 2 is a side elevational view thereof; and Fig. 3 is a rear elevational view thereof.

I claim:

The ornamental design for a doll, as shown.
RUTH J. HEYMAN.
